UNITED STATES PATENT OFFICE.

EARL K. ATWOOD, OF WATERVILLE, MAINE.

FEEDING MECHANISM FOR CONDITIONING MACHINES.

1,253,923.

Specification of Letters Patent. Patented Jan. 15, 1918.

Application filed February 5, 1917. Serial No. 147,242.

To all whom it may concern:

Be it known that I, EARL K. Atwood, a citizen of the United States of America, and a resident of Waterville, in the county of

5 Kennebec and State of Maine, have invented certain new and useful Improvements in Feeding Mechanism for Conditioning Machines, of which the following is a specification.

10 In order to prepare filling yarns for the loom it is now almost the universal practice in mills to deliver the bobbins of filling yarn to a conditioning machine, such, for instance, as that shown in U. S. Patent No.

15 910,602, issued Jan. 26, 1909, to H. F. Straw.

This conditioning machine is provided with a traveling apron upon which the bobbins rest while being subjected to a super-saturated atmosphere of a comparatively uniform temperature, and the general practice is to deliver the bobbins by hand to the apron from a table at one end of the machine, or from the bobbin box when raised by a chain fall to a point adjacent said table.

25 This was very objectionable as it required an expensive man to do this particular work, and owing to the fact that the work was so hard it has been difficult to get men to do it or keep at it when once obtained.

30 There is another objection to feeding by hand due to the fact that the operators were liable to feed too fast or too slow and consequently the yarn on the bobbins would not be properly conditioned, and oftentimes this required the use of more steam and water than was actually necessary.

The object of the present invention is to overcome these difficulties and provide a uniform feed to the apron of the conditioning machine.

40 The invention consists of a hopper into which the bobbins to be conditioned may be dumped from the bobbin boxes, said hopper having a movable bottom and at one end an inclined ribbed apron adapted to separate the bobbins from the mass within said hopper and deliver them to the traveling apron of the conditioning machine.

45 For the purpose of illustrating the invention one preferred form thereof is illustrated in the drawings, this form having been found to give satisfactory and reliable results, although it is to be understood that the various instrumentalities of which the invention consists can be variously arranged and organized, and that the invention is not

limited to the precise arrangement and organization of these instrumentalities as herein shown and described.

60 Of the drawings:

Figure 1 represents an elevation of an apparatus embodying the principles of the present invention, and showing a portion of one end of a conditioning machine.

Fig. 2 represents a transverse vertical section of same on line 2—2 on Fig. 1.

Fig. 3 represents a longitudinal vertical section of same on line 3—3 on Fig. 2, and

70 Fig. 4 represents a horizontal section on line 4—4 on Fig. 3.

Similar characters designate like parts throughout the several figures of the drawings.

In the drawings, 10 represents the receiving end of a conditioning machine, said 75 machine being provided with a traveling apron 11, as indicated in Fig. 3 of the drawings. Adjacent to the end of said machine 10 is positioned a hopper 12 having a vertical end 13 and two vertical sides 14. 80 The end 13 is reinforced by means of a frame 15, to which is secured a strap 16 provided with downwardly extending feet 17 by which said strap may be secured to the floor by means of bolts 18.

85 The sides 14 have upwardly inclined extensions 19 which are parallel to each other and are adapted to fit in between the sides 20 of the receiving end of the conditioning machine 10. The upper ends of the extensions 19 are provided with bearings in which 90 rotate the shaft 21 having a roll 22 secured thereto between said extensions. The sides 14 are also provided with bearings in which 95 revolves a shaft 23 having a roll 24 thereon.

100 Mounted upon the rolls 22 and 24 is an endless apron 25 to the outer face of which are secured a plurality of triangular wooden cleats 26, the front face of each of which has secured thereto a metal plate 27. Secured to the sides 14 and the extensions 19 are inwardly extending inclined flanges 28 extending over the marginal portions of said apron 25.

105 The upper marginal portions of the sides 14 flare out as at 29 and said sides have secured to the inner faces thereof the inclined flanges 30. Beneath the flanges 30 is located the endless belt 31 mounted upon drums 32 secured to revolvable shafts 33 and 34.

110 The shaft 33 has secured to one end a driving pulley 35 and to the opposite end

thereof a sprocket wheel 36 which is connected by means of a sprocket chain 37 with the sprocket wheel 38 secured to the shaft 34. The shaft 34 also has secured thereto a pulley 39 connected by a belt 40 with a small pulley 41 secured to the outer end of the shaft 23. By means of the driving pulley 35 motion is imparted to the chains 37 and belt 40 in the direction of the arrows on Fig. 1 of the drawings.

This driving mechanism causes the apron 25 and the belt 31 to be moved in the direction of the arrows on Fig. 3 of the drawings. It is obvious that the driving mechanism is so constructed that the apron 25 travels considerably faster than the belt 31. The belt 31 has secured thereto a plurality of wooden strips 42 extending transversely of said belt and flush with the upper face of said strips is a transverse member 43 secured at opposite ends to the sides 14—14.

Secured to this cross member 43 is a curved plate 44 extending downwardly adjacent to the outer edges of the cleats 26—27.

The cleats 26 and 27 are all secured to the apron 25 with their outer ends adjacent to the inner edges of the inclined flanges 30, and all of the cleats are at regular intervals apart. These cleats, however, are made of various lengths, some, such as 45 extending clear across the apron, while others, such as 46, extend more than half way across, while still others, such as 47, extend inwardly only a short distance, thus leaving irregular spaces on the apron 25 entirely free from cleats.

When the bobbins are dumped into the hopper 12 they rest upon the movable bottom 31—42, and as this moves in the direction of the arrow on Fig. 3 of the drawings, the bobbins are carried over the upper face of the cross member 43 and are picked up by means of the cleats 26—27 and carried by the apron 25 to a point above the apron 11 of the conditioning machine 10.

As the apron passes around the revolute supporting member 22 the bobbins are dropped upon this apron 11. As the apron moves around the revolute supporting member 24, the cleats 26 thereon move along the inner face of the curved member 44, and when the irregular spaces on apron 25 between the shorter cleats reach the top of said member 44, some of the bobbins in the hopper 12 are permitted to drop down between said member and the supporting member 24. These bobbins will be carried up-

wardly with the apron by the longer cleats below said irregular spaces.

By means of this device some of the bobbins are continually being separated from the mass of bobbins in the hopper 12 and carried by the apron 25 at a uniform speed to the conditioning machine 10.

When this apparatus is used in connection with a conditioning machine the high cost of labor is dispensed with, the only man required about the machine being one to take away the cases of yarn as they become filled after going through the conditioning machines, and this man is capable of looking after several machines.

It is believed that the operation and many advantages of this invention will be fully understood from the foregoing description.

Having thus described my invention, I claim:

1. In a device of the class described, a hopper having side walls; a movable bottom therefor; an inclined movable apron at one end of said hopper; and transverse cleats of various lengths on said inclined apron extending inwardly with their outer ends adjacent the inner faces of said side walls.

2. In a device of the class described, a hopper having side walls; a movable bottom therefor; an inclined movable apron at one end of said hopper; and a plurality of transverse cleats on said inclined apron extending inwardly from said side walls thereof and with their inner ends staggered.

3. In a device of the class described, a hopper; a movable bottom therefor; an inclined movable apron at one end of said hopper; and transverse cleats of various lengths on said inclined apron and extending from the sides of said apron.

4. In a device of the class described, a hopper having side walls; a movable bottom therefor; an inclined movable apron at one end of said hopper; a plurality of transverse cleats on said inclined apron and extending from one side wall to the other; and other transverse cleats of various lengths interposed between the first mentioned cleats with their outer ends adjacent to said side walls and their inner ends staggered.

Signed by me at Waterville, Maine, this 20th day of January, 1917.

EARL K. ATWOOD.
